DESIGN FOR A COMBINED BOOK, MAGA- ZINE, NEWSPAPER RACK, AND SMOKING STAND

Louis Reis, New York, N. Y.

Application April 26, 1945, Serial No. 119,221

Term of patent 7 years

(Cl. D85—2)

To all whom it may concern:

Be it known that I, Louis Reis, a citizen of the United States and a resident of the city of New York, in the county of Bronx and State of New York, have invented a new, original, and ornamental Design for a Combined Book, Magazine, Newspaper Rack, and Smoking Stand, of which the following is a specification, reference being had to the accompanying drawing, forming a part thereof.

The figure is a perspective view of a combined book, magazine, newspaper rack, and smoking stand showing my design.

I claim:

The ornamental design for a combined book, magazine, newspaper rack, and smoking stand, substantially as shown.

LOUIS REIS.
